UNITED STATES PATENT OFFICE.

DAVID TERRY, OF SACRAMENTO, CALIFORNIA.

UNLOADING APPARATUS.

Application filed May 9, 1922. Serial No. 559,503.

To all whom it may concern:

Be it known that I, DAVID TERRY, a citizen of the United States, and a resident of Sacramento, county of Sacramento, and 5 State of California, have invented a new and useful Unloading Apparatus, of which the following is a specification.

My invention relates in general to an unloading apparatus of the conveyer type and 10 has reference more particularly to an improved means for conveniently unloading freight cars and the like of the bottom dump type.

The salient features of the invention 15 reside in the simplicity of construction which enables the same to be operated on a practical basis and capable of quickly and efficiently transferring the contents of loaded cars from the cars to a point where it may be 20 disposed for further handling.

The preferred features of the invention are illustrated in the accompanying drawing, but in considering the same it should be noted that I have selected the arrangement 25 shown only for illustrating purposes as many changes may be made in detail without departing from the spirit of the invention as defined in the subjoined claims. In said drawing, Figure 1 is a view in cross-section 30 of a conventional type of freight car showing the application of the invention and with the conveyer apparatus in side elevation; Figure 2 is a plan view of the conveyer unit; Figure 3 is a cross-section through 35 the conveyer unit on the line 3—3 Figure 1; Figure 4 is a view in side elevation and partly in section of a freight car showing the application of the invention and with the conveyer unit in cross-section; Figure 5 is 40 a view in front elevation of the discharge and of one of the transverse hoppers and Figure 6 is a view in side elevation of one of the transverse hoppers.

Referring now to the drawing in detail 45 (A) represents a freight car constructed along conventional lines having the usual bottom dump construction consisting of the chutes (B) and (C) each of which having a door closure (D) pivotally connected as 50 at (C) adapted to swing to and from closing relation relative to the chutes and actuated by the link structure (E).

According to my invention the freight car 55 (A) to be unloaded is run over a trestle structure (F) having tracks (G) and adapt-

ed to elevate the car above the conveyer apparatus to be presently described.

Positioned under each of the chutes (B) and (C) is arranged a transfer hopper (5), the same being suspended at its closed rear 60 end from the outside of the car by long hook rods (6) arranged in pairs, one for each hopper, having hooks (7) at their upper ends made to hook over the sides of the car and with loops at their lower ends 65 adapted to receive the hooks (8) on the closed ends of the hoppers. The discharge ends of the hoppers are suspended by providing eyes (9) made to receive the hooks (10) which in turn are suspended in any 70 suitable manner from the bottom of the car.

Each of the transfer hoppers are made with a sloping bottom so that the material deposited into the same will gravitate to the discharge and where it may be released by a 75 sliding door (10) which controls the effective discharge area of the discharge end of the hopper. The car to be unloaded with the hoppers applied is run over the trestle structure (F) so that the discharge ends 80 of the hoppers (5) which are presented in confronting relation as best shown in Figure 1 are presented over the receiving hopper (12) provided in the trestle structure (F) and the outlet for the hopper (12) is lined 85 up with the belt (13) of the conveyer unit. The conveyer unit includes a suitable supporting structure or frame (14) having several sets of rollers (15) over which the belt (13) travels with the rollers positioned 90 to form a trough like receptacle for the belt. The frame (14) is pivoted as at (16) upon a pedestal mounting (17) so as to leave the frame (14) adjustable in various horizontal angular planes with the adjustment maintained by the standard or standards (18) at the outer end of the frame (14). By changing the vertical plane of the standard or standards (18) the horizontal angular 95 plane of the conveyer unit may be regulated as desired. Positioned at the outer end of the frame (14) is a wheel (19) over which the belt (13) traverses. The wheel being fixed in the mounting (20) with the mounting having a longitudinal sliding connection relative to the frame so that a screw or the like (21) may be used to tighten or loosen the belt (13) by sliding the mounting (20) upon the frame.

The opposite end of the frame (14) is 110

made with the wheel co-axially positioned in back of a gear, which will be presently described, and the belt traverses over this wheel at this end of the frame. The belt 5 travels toward the outer end of the frame and returns under the same as shown in dotted lines so that the material released from the car into the receiving hopper (12) may be conveyed away from the car and deposited upon the ground or in a receptacle or wagon positioned at the outer end of the frame (14). As a convenient means of driving the belt (13) I propose to use an engine (23) as a part of the conveyer unit, the same 10 having a driving pulley (24) on its shaft with a belt (25) connecting the driving pulley (24) in driving relation with a larger belt pulley (26) mounted upon the shaft (27) and with a small driving gear (28) on the opposite end of the shaft (27) in mesh with the relatively large gear (29) mounted upon the shaft (30) co-axially of the wheel (31) for the belt (13) previously mentioned. In order that the engine may continue to 15 run without driving the belt (25), the clutch (32) is arranged on the engine shaft as best shown in Figure 2. The clutch is also arranged so that the driving belt (25) may be at a stand still and at the same time the 20 power of the engine may be used for driving the winch (33) through the medium of the mesh gears (34).

From the above it will be readily seen that 25 with my equipment the material in the car may be conveyed away in a very simple manner. It will require no expert skill to operate the apparatus nor are there any delicate parts of machinery connected with the same to become out of order. Of course, it is understood that in most standard car equipment such as the car (A) there are two sets 30 of chutes arranged in confronting relation on opposite sides of the center line of the car. I require, or at least prefer, to use one transfer hopper for each opening so that when in operation there will be two transfer 35 hoppers in use, one for each of the chutes. Of course, I can use four transfer hoppers so as to unload the car from all four doors, but to accommodate the equipment to this 40 use the trestle structure as well as the receiving hopper must be built to accommodate the amount of material that would be discharged at one time; in most cases, it would 45 be desirable to discharge one end of the car from a pair of the transfer hoppers, then move the car up to bring the other openings

over the receiving hopper (12) and to either transfer the transfer hoppers to the openings thus moved up or to use all four transfer hoppers at one time leaving two of them 60 idle until the car is moved up to move them over the receiving hopper.

I claim:

1. In combination with a bottom dump 65 car, a chute having an inclined bottom and adapted to lie transversely under the car with one end near the side thereof, a hook rod adapted for hooking to the edge of the car and connected to the end of the chute. 70
2. In combination with a bottom dump 75 car, a chute having a shallow and a deep end and an inclined bottom, two hook rods pivotally connected to the shallow end and adapted to hook to the side of the car to support the chute adjacent the bottom thereof. 80
3. In combination with a bottom dump car, a chute having a shallow and a deep end and an inclined bottom, a gate at the deep end of the chute, two hook rods pivotally connected to the shallow end and adapted to hook to the side of the car to support the chute adjacent the bottom thereof. 85
4. In combination with a bottom dump 90 car, a chute having a shallow and a deep end and an inclined bottom, a gate at the deep end adjacent the bottom of the car, two hook rods pivotally connected to the shallow end and adapted to hook to the side of the car to support the chute adjacent the bottom thereof. 95
5. In combination with a bottom dump 100 car, a chute having a shallow and a deep end and an inclined bottom, a gate at the deep end of the chute, suspension links secured to both sides of the chute at its deep end, two hook rods pivotally connected to the shallow end and adapted to hook to the side of the car to support the chute adjacent the bottom thereof. 105
6. In combination with a bottom dump 110 car having fixed double discharge chutes arranged longitudinally thereof, a pair of auxiliary chutes positioned under the car and each, respectively, under one of the fixed chutes, said auxiliary chutes each having a shallow and a deep end, and detachable means for holding the chutes adjacent the car bottom with their deep ends in confronting relation.

DAVID TERRY.
